Primary Examiner—Philip S. Hyder*(74) Attorney, Agent, or Firm*—Joseph J. Previto**CLAIM**

The ornamental design for a foldable utility knife, as shown and described.

DESCRIPTION

FIG. 1 is a perspective view of my new design showing it in an unfolded position.

FIG. 2 is a top view thereof.

FIG. 3 is a side view thereof.

FIG. 4 is a front view thereof.

FIG. 5 is a rear view thereof.

FIG. 6 is a bottom view thereof.

FIG. 7 is another side view thereof.

FIG. 8 is a side view thereof showing it in a partially folded position; and,

FIG. 9 is a side view thereof showing it in a folded position. The broken line showing the blade is for illustrated purposes only and forms no part of the claimed design.
